UNITED STATES PATENT OFFICE

JAMES HARRIS GRIFFIN, OF ST. HELENS, ENGLAND, ASSIGNOR TO PILKINGTON BROTHERS LIMITED, OF LIVERPOOL, ENGLAND

PROCESS OF AND APPARATUS FOR WASHING OFF THE FELTS OF POLISHER RUNNERS IN GLASS-POLISHING APPARATUS

Application filed June 17, 1926, Serial No. 116,524, and in Great Britain July 7, 1925.

This invention relates to the process of and apparatus for washing the felts of polisher runners in glass polishing apparatus and has for its object a process and apparatus whereby the felts of any runner can be washed while the runner is in position above the polishing apparatus.

The invention is more particularly applicable to the continuous glass polishing process and apparatus.

In all glass polishing apparatus in which rouge embedded in felts is employed as the polishing medium, the rouge is supplied to the felts during a portion of the period of polishing, and then the supply is stopped, the remainder of the polishing being effected by the rouge embedded in the felts, which has a finer polishing effect as the polishing operation is continued. When the polishing operation is finished, and the felts have to be used for a new polishing operation, the rouge embedded in the felts is too fine for effective working at the early stages of the operation, and it is washed out of the felts by subjecting them to a plentiful supply of water, before a fresh supply of rouge is made.

In ordinary glass polishing apparatus of the rotating table type, the above mentioned different treatments of the felts succeed one another with the succession of different polishing operations, but in the continuous polishing apparatus in which the glass travels slowly beneath rotating, but otherwise stationary, polishing runners, each one of these runners is doing the same work all the time, and it has been found that their polishing action is not maintained effective by continuously supplying their felts with rouge, by reason of the amount of rouge embedded in the felts, which has become spent by continued action.

According to this invention, the felts of any polishing runner are, from time to time, brought into condition for effective polishing by washing the spent rouge and dirt out of them and renewing the supply of rouge, without removing the felts or any portion of the runner from their position above the glass, and without interrupting the motion

of the tables of the polishing apparatus or the action of the other polishing runners.

In the accompanying drawings:—

Figure 1 is a transverse section of the polishing apparatus showing in elevation the washing apparatus;

Figure 2 is a side elevation of the same, and

Figure 3 is a transverse section of the polishing apparatus showing an alternative form of the washing apparatus, and omitting certain portions of the polishing apparatus, which are the same as those shown in Figure 1.

Referring to Figures 1 and 2, the series of tables 1, sliding on guides 2, is driven in the customary way through a rack 3. A framework 4^a, 4^b, 4^c, on pillars 5 carries, in bearings 6, a runner shaft 7 with frame 8, and two polishing pads 9. By means of a handwheel 10, screw 11 and lever 12 engaging a collar 13 between collars 14 on the shaft 7, the runner can be raised and lowered; in said figures it is shown in its raised position. A pair of runway girders 15 are attached to the framework girders 4^a, one on each side of the runner, and similar runway girders are provided for each runner of the polishing apparatus. (In Figure 2 the girders 15 are behind the girders marked 16). Another pair of runway girders 16 is supported at the side of the polishing apparatus by a travelling framework 17 provided with wheels 18 running parallel with the polishing apparatus, on rails 19. The runway girders 16 are adapted to register with the runway girders 15 and are shown in the drawings in registration therewith.

A washing table 20 is suspended from the runway girders 15 by means of standards 21 carrying rollers 22 running on the girders, and, when the girders 16 are in register with said runway girders 15, the table 20 can be run from the position in which it is shown in full lines, where it is over the table 1 and under the polishing pads 9, on to the travelling framework 17, where it is shown in dotted lines.

The washing table 20 is a plate of glass or other smooth substance and may be provided

with shields to prevent the water used in washing being thrown out. A pipe 26 is provided to supply water to the table.

The method of operation is as follows:—

- 5 The travelling framework 17 is run on the rails 19 to bring the runway girders 16 thereof into register with the runway girders 15 of the particular polishing runner, the felts of which are to be washed. The polishing 10 runner is raised into the position shown, and then the washing table 20 is run beneath it along the runway girders 16 and 15; the polishing runner is then let down on to the washing table 20 and is rotated thereon while 15 water is supplied in quantity through pipe 26. When the washing is completed, the washing table 20 is removed by reversal of the above described operations, and the polishing runner is in condition to resume its 20 operation on the glass on the table 1.

In the alternative form of apparatus shown in Figure 3, in which the same reference numerals indicate the same parts as in Figures 1 and 2, the washing table 20 is permanently 25 over the table 1 but is capable of being run along it by means of its supporting wheels 23 running on rails 24. When not in operative position, the table 20 is kept in the space between two polishing runners or at the end 30 of the polishing apparatus. With this form of the apparatus the felts of the polishing runners are conveniently washed in succession from one runner to the next along the whole length of the polishing apparatus. 35 Hooks 25 are then provided on the table 20 whereby the table may be lifted by a crane and travelled and let down into position on the rails 24 at the start of the apparatus or between any two polishing runners.

40 The table 20 may be faced with glass.

The invention is not confined to the two forms of apparatus shown and described which are given as convenient forms and as examples of means whereby the process may 45 be carried out.

In the above specification the invention has been described with reference to polishing by the action of rouge and water embedded in felts because these materials are those ordinarily used, but it is equally applicable to any other polishing medium and liquid and any suitable material other than felt. Further, the washing device may be applied to a group of polishing runners instead of to 55 only a single runner, and in the specification and claims the term "polishing runner" is to be taken as including a group of polishing runners, and the term "felts" is to be taken as including suitable polishing materials 60 other than felt.

The invention is also applicable to glass polishing processes and apparatus in which a plurality of polishing runners are used which are to be used, as far as is practicable, 65 continuously.

Having described my invention, I declare that what I claim and desire to secure by Letters Patent is:—

The combination with a plurality of successively mounted polishing heads and a plurality of traveling polishing tables movable beneath said heads, of tracks disposed parallel to the path of movement of said tables, a pair of tracks disposed adjacent to each head and in a plane above the surface of the tables, a truck on the first named tracks, a wheeled table on said truck and movable to the second-named tracks into position between the polishing head and the first-named tables when the former is moved vertically upward clear of the table, and means on said wheeled table for cleansing the polishing heads.

In testimony whereof I have affixed my signature hereto.

JAMES HARRIS GRIFFIN.
